ARTIFICIAL ARM

Charles F. Bender, Atlanta, Ga.

Application August 16, 1947, Serial No. 768,955

3 Claims. (Cl. 3—12)

1

This invention relates to artificial arms for use in cases where the natural arm has been removed at a point above the elbow.

An object of my invention is to provide an artificial member particularly adapted for working purposes which can be bent at the elbow without assistance from the remaining natural arm.

Another object of my invention is to provide an artificial arm which is simple and rugged in construction, efficient in operation and inexpensive to manufacture.

Further objects and advantages of my invention will be apparent from the following description taken in connection with the accompanying drawing wherein like characters of reference designate corresponding parts in the several views, and wherein:

Fig. 1 is a back view showing the arm in place.

Fig. 2 is a fragmentary side view showing details of the elbow joint with the arm in adduction.

Fig. 3 is a fragmentary side view showing details of the elbow joint with the arm in adduction.

Referring more in detail to the drawing, an upper arm socket member 11 is secured in place on the stump of the upper arm by means of suitable harness 12 which is buckled about the shoulders. A forearm member 13 is hinged to the upper arm member 11 by means of a hinge pin or elbow bolt 14 which extends from side to side of the joint.

A control arbor 15 is eccentrically mounted on the elbow bolt 14 and is securely locked in place by means of set screw 16. One end of an activating control funicle 17 is secured to the control arbor 15, adjacent to a point on the periphery thereof substantially farthest from the elbow bolt 14, by means of clamping screws 18 and lock nut 19. The clamping screw 18 also extends through a slot 20 cut in the control arbor 15 to enable the control arbor to fit snugly about elbow bolts of slightly varying size.

The activating funicle 17 extends around the control arbor 15, under the end of a flexible stabilizing bar 21 and out through a hole 22 in the rear of the upper arm member 11. This end of the activating funicle is secured to the shoulder harness 12 by suitable means such as buckle 23.

The stabilizing bar 21, which is made of spring steel or other suitable material, is securely fastened at one end to the upper arm member 11, and is provided with a receptacle or hole 24 to

2

receive a locking pin 25 which is mounted on the control arbor 15.

To move the arm from adduction to abduction, only a slight forward shrug of the shoulder is necessary to start the forearm 13 to swing and this shrug of the shoulder applies tension on the activating funicle 17 which quickly lifts the forearm by traction about the eccentrically mounted centrifugal control arbor 15 and by reason of the end secured thereto. The tension on the activating funicle, and hence the position of the forearm 13, is at all times under the complete control of the wearer. Tension on the funicle 17 lifts the free end of the stabilizing bar 21, and as the locking pin 25 approaches the receptacle 24 the tension may be slackened sufficiently to permit the stabilizing bar to spring downwardly sufficiently to receive the pin 25, whereupon the arm is securely locked in abduction. It is of course obvious that more than one receptacle 24 may be provided in the stabilizing bar, if desired, to receive the pin 25 and lock the forearm in slightly varying positions. Also, it will be obvious that the position of the arm may be varied by adjusting the position on the elbow bolt 14 by means of set screw 16.

To move the arm from abduction to adduction, again only a slight forward shrug of the shoulder is necessary to apply tension on the activating funicle 17 sufficient to raise the free end of stabilizing bar 21 to clear the end of locking pin 25. The lowering of the forearm 13 is under the complete control of the wearer by means of the tension on funicle 17.

Having thus fully described my invention, I claim:

1. An artificial arm comprising an upper arm member, a forearm member joined thereto by a hinge pin, a control arbor eccentrically mounted on said pin, a control funicle having one end secured to said arbor, stabilizing means mounted on said upper arm member, and locking means on said arbor for cooperation with said stabilizing means for locking said arm in abduction, said control funicle being arranged to move said stabilizing means to release said locking means.

2. An artificial arm comprising an upper arm member, a forearm member hinged thereto, a hinge pin extending from side to side of the joint, a control arbor eccentrically mounted on said pin, a flexible stabilizing bar mounted on said upper arm member, locking means secured to said control arbor for cooperation with said bar to lock the arm in abduction, and a control funicle extending partially around said arbor

and having one end secured to said arbor for controlling movement of said forearm member, said control funicle being arranged to flex said stabilizing bar to release said locking means.

3. An artificial arm comprising an upper arm member, a forearm member hinged thereto, a hinge pin extending from side to side of the joint, a control arbor eccentrically mounted on said pin, an activating control funicle extending partially around said arbor and having one end secured to said arbor and the other end arranged to be secured to a shoulder harness for controlling movement of said forearm member, and means for locking said forearm in abduction, said control funicle being arranged to actuate said last mentioned means to release the same.

CHARLES F. BENDER.
